(57) **CLAIM**

The ornamental design for a handheld blade steel as shown and described.

DESCRIPTION

The present application is filed contemporaneously with U.S. patent application Ser. No. 17/717,998, entitled Handheld Blade Steel, the entire disclosure of each of which is hereby incorporated by reference herein.

FIG. 1 is a front perspective view of a handheld blade steel embodying our design;

FIG. 2 is a rear perspective view of the handheld blade steel as shown in FIG. 1;

FIG. 3 is a front perspective view of the handheld blade steel taken at a different angle than shown in FIG. 1;

FIG. 4 is a front view of the handheld blade steel as shown in FIGS. 1-3;

FIG. 5 is a side view of the handheld blade steel as shown in FIGS. 1-4;

FIG. 6 is a side view of the handheld blade steel opposite that as shown in FIG. 5;

FIG. 7 is rear view of the handheld blade steel as shown in FIGS. 1-6;

FIG. 8 is a top view of the handheld blade steel as shown in FIGS. 1-7; and,

FIG. 9 is a bottom view of the handheld blade steel as shown in FIGS. 1-8.

In the drawings, the broken lines shown depict environmental subject matter only and form no part of the claimed design.
